UNITED STATES PATENT OFFICE.

ARTHUR SAMUEL PIERSON, OF MORRISTOWN, NEW JERSEY.

TENSION OR REINFORCING DEVICE FOR USE IN CONCRETE STRUCTURES.

No. 810,221.

Specification of Letters Patent.

Patented Jan. 16, 1906.

Application filed May 10, 1905. Serial No. 259,858.

To all whom it may concern:

Be it known that I, ARTHUR SAMUEL PIERSON, a citizen of the United States, residing at Morristown, in the county of Morris and State of New Jersey, have invented certain new and useful Improvements in Tension or Reinforcing Devices for Use in Concrete Structures of which the following is a specification, such as will enable those skilled in the art to which it appertains to make and use the same.

This invention relates to what are known as "fireproof" structures or buildings, and particularly buildings of this class which employ columns, beams, girders, floors, and the like composed of concrete reinforced with metal bars, ties, or other devices of various kinds and classes which are embedded in the concrete material; and the object of the invention is to provide an improved tension or reinforcing device for use in structures of the class specified and which may be employed in columns, beams, girders, and flooring composed of concrete or similar material or in making slabs or plates of any size for use in vault-lights or in similar places.

The invention is fully disclosed in the following specification, of which the accompanying drawings form a part, in which the separate parts of my improvement are designated by suitable reference characters in each of the views, and in which—

Figure 1 is a side view of a tension or reinforcing device of the class specified made according to my invention, part of the construction being broken away; Fig. 2, a section on the line 2 2 of Fig. 1; Fig. 3, a view similar to Fig. 1, but showing a modification; and Fig. 4, a section on the line 4 4 of Fig. 3.

In the practice of my invention, as shown in Figs. 1 and 2, I provide a trough-shaped bar *a*, composed of a flat sheet of metal folded to form a deep groove *a*² in the top thereof, and secured in this groove are continuous rods *b* and *c*, bent at regular intervals to form elbows or knees *b*² and *c*², the angle of the bends being approximately right angles in the form of construction shown, and these rods *b* and *c*, bent in the manner described, are inserted into the groove *a*² in the bar *a*, and the opposite side walls *a*³ are crimped, bent, or forced inwardly between the separate elbows or knees of the rods *b* and *c* and also between the separate side members of each elbow or knee of each of said rods, as

clearly shown in Figs. 1 and 2, so as to secure the rods *b* and *c* in the bar *a*. The crimping or forcing inwardly of the sides of the bar *a* may be done by means of a hammer or in any desired manner, and with this form of construction it will be necessary to form the bar *a* of material thin enough to permit of this operation.

In the construction shown in Figs. 3 and 4 the rods *b* and *c* are held in place by pins *d*, which are passed transversely through the opposite side walls of said bar and through or within the elbows or knees of each of said rods, which are placed within the side walls of the bar, and with both forms of construction the rods *b* and *c*, bent in the manner described, are securely held in the bar *a*. With the form of construction shown in Figs. 3 and 4 the bar *a* may be made in any desired manner, and any other suitable means may be employed for securing the rods *b* and *c* to or in said bar, and my invention is not limited to the forms of the bar *a* herein shown and described, as other forms may be provided, if desired.

A tension or reinforcing device made in this manner possesses the greatest possible tensile resistance and also the greatest possible resistance against compression in proportion to the amount of metal employed, and in practice a tension or reinforcing device made in this manner may be employed in columns, beams, girders, floor and ceiling construction, or in slabs, a number of said devices being placed parallel with each other and the cement, concrete, or other material being embedded around the same in the manner of other devices of this class and as indicated in dotted lines at *e*, and although I have shown but one form of bar—namely, what is known as a "channel-bar"—it will be apparent that a bar of any desired form may be employed and the rods *b* and *c*, bent in the manner described, secured thereto in any preferred way.

In addition to the uses herein specified for my improved tension or reinforcing device or devices the same may also be used in the construction of railway ties, sleepers, and the like, and it will also be apparent that a device made in this manner may be employed in certain forms of structural work, as a lattice-truss or other independent feature, without being embedded in, connected with, or otherwise relating to concrete-work. It will also

be apparent that instead of bending the rods *b* and *c* at regular intervals to form knees or elbows forming substantially right angles the said rods may be bent at regular intervals to form upwardly and downwardly directed loops of any shape, the sides of said loops or bends when the rods are secured in the bar *a*, as herein described, crossing each other above the bar and projecting a certain distance above the bar, the particular shape or form of the loops or bends *b*³ and *c*³ being immaterial.

Having fully described my invention, what I claim as new, and desire to secure by Letters Patent, is—

- 15 1. A tension or reinforcing device of the class described, comprising a bar and continuous rods bent at regular intervals to form oppositely-directed loops or elbows, said rods being placed together side by side so that the side portions of the loops or elbows cross each other, and the loops or elbows which project in the same direction being secured to said bar, substantially as shown and described.
- 20 2. A tension or reinforcing device of the class described, comprising a channel-bar and continuous rods bent at regular intervals to form loops or elbows, said rods being placed together side by side so that the side portions of said loops or elbows cross each other and the loops or elbows which project in the same direction being secured to said bar, substantially as shown and described.
- 25 3. A tension or reinforcing device of the class described, comprising a bar and a plurality of continuous rods bent at regular intervals to form oppositely-directed loops or elbows, said rods being placed side by side so that the side portions of the loops or elbows cross each other and the loops or elbows which project in the same direction being permanently secured to said bar, substantially as shown and described.
- 30 4. A tension or reinforcing device of the class described, comprising a bar and a plurality of continuous rods bent at regular intervals to form loops or elbows, said rods being placed together side by side so that the side portions of said loops or elbows cross each other and the loops or elbows which project in the same direction being secured in said bar, substantially as shown and described.

in the same direction being secured in said bar, substantially as shown and described.

3. A tension or reinforcing device of the class described, comprising a channel-bar 35 and continuous rods bent at regular intervals to form loops or elbows, said rods being placed together side by side so that the side portions of said loops or elbows cross each other and the loops or elbows which extend 40 in the same direction being secured in said bar by means of pins passed through the side walls thereof and through said loops or elbows, substantially as shown and described.

4. A tension or reinforcing device of the 45 class described, comprising a bar and a plurality of continuous rods bent at regular intervals to form oppositely-directed loops or elbows, said rods being placed side by side so that the side portions of the loops or elbows 50 cross each other and the loops or elbows which project in the same direction being permanently secured to said bar, substantially as shown and described.

In testimony that I claim the foregoing as 55 my invention I have signed my name, in presence of the subscribing witnesses, this 8th day of May, 1905.

ARTHUR SAMUEL PIERSON.
